UNITED STATES PATENT OFFICE

2,432,563

REFRIGERATOR CABINET

Earl D. Drake, Greenville, Mich., assignor to Gibson Refrigerator Company, Greenville, Mich., a corporation of Michigan

Application January 13, 1944, Serial No. 518,052

6 Claims. (Cl. 20—38)

1

This invention relates to cabinet doors, and more particularly to doors for refrigerator cabinets.

In the past considerable difficulty has been experienced, particularly in refrigerator doors of the so-called "full covering" type, in obtaining a good heat seal between the door and the refrigerator cabinet to which it is attached. Any difference in parallelism of the front of the cabinet and the inner face of the door results in a variation in contact between the door and the sealing gasket, or the cabinet and gasket, depending upon which member the gasket is attached to, and heat leaks occur. It is nearly impossible to make a door from sheet material and provide the requisite parallelism.

The door can be made flexible enough to permit it to warp slightly to conform to the cabinet, but such a door is prone to sag and lose its generally rectangular shape. That causes difficulty in maintaining the heat seal.

The present invention is designed to overcome these difficulties by providing a door that is relatively flexible in a direction perpendicular to the plane of the door to permit it to conform to the shape of the front of the cabinet, yet is relatively rigid in the plane of the door to prevent sagging of the latter.

This object is attained in part by forming a flexible outer door pan of relatively thin sheet material and providing the outer door pan with means for stiffening it in the plane of the door. At the same time the stiffening means is so constructed, and so connected to the door, that the latter is relatively flexible in a direction perpendicular to the door. The inner door panel which must be provided in order to properly seal the insulation from the entrance of moisture, as well as to ornament the door, is relatively loosely connected to the door by a molding within which the inner panel is slidably received.

The objects of the present invention will become more apparent in the following specification when read in connection with the accompanying drawings, wherein:

Figure 1 is a front elevational view of a refrigerator cabinet having a door embodying the invention;

Figure 2 is an elevational view of the door taken from the inner side thereof and with the inner door panel and its associated molding removed;

Figure 3 is a fragmentary sectional view of the complete door taken on substantially the line 3—3 of Figure 2;

Figure 4 is a pictorial view of the equalizing means for the door stiffener; and

Figures 5, 6 and 7 are respectively fragmentary cross-sectional views of the completed door taken on the lines 5—5, 6—6 and 7—7 of Figure 2.

Figure 1 of the drawings illustrates a refrig-

2

erator cabinet 1 to which a door 10 is connected by hinges 8 at one lateral side thereof. The door is provided with a latch (not shown) having a handle 9.

The door 10 comprises an outer door pan 11 of generally concavo-convex shape. It has a relatively flat front, outer wall, and a perimetrical side wall 12 extending laterally therefrom. The perimetrical side wall may be formed from separate pieces attached to the outer wall, but preferably the entire outer door pan is formed from a single piece of sheet material, preferably either sheet metal or plastic. About the top and two upright sides of the side wall is an inturned flange 13 which substantially parallels the outer wall of the door. The flange 13 is notched at the two upper corners of the door, as indicated at 14, for a purpose which will presently appear.

The bottom portion of the side wall 12 is provided with an angle member 16 having an upright flange 15 located in the same plane as the flange 13.

A relatively heavy reinforcing angle member 16, bent into U-shape, extends about the top and two sides of the door. The vertical leg of the angle member 16 is juxtaposed to the inside surface of the flange 13 and is secured thereto in any suitable manner.

The parts of the door just described are essentially quite flimsy unless made of relatively heavy material. Hence, it is braced by a stress equalizing stiffening device. In the present invention the stiffening device comprises four elongated tie members 17 which are pivotally connected at their outer ends to the angular reinforcing member 16 adjacent the corners of the door. The tie members are arranged in pairs converging toward the center of the door. It will be noted that the vertical leg of the angular reinforcing member is offset toward the interior of the door, as at 18, to receive the ends of the tie members 17 in such a manner that the latter will not extend beyond the plane of the flanges 13 and 15. The outer ends of the tie members are received in the notches 14 in the flange 13.

The ends of the tie members adjacent each other are connected together by an equalizer denoted in general by the numeral 19. The equalizer is shown best in Figure 4. It comprises two bars 20 which are normally spaced apart and which are generally parallel to each other. Each bar 20 is formed of two strips of metal juxtaposed to each other to form spaced apart parallel openings 21 extending in the plane of the door. The two openings 21 receive threaded bolts 22. The heads of the bolts 22 engage one of the bars 20. Nuts 23 threaded on the other ends of the bolts engage the other bar 20.

The ends of each bar 20 are pivotally connected 60 by rivets 24 to the adjacent ends of one pair of

tie members 17. The rivets also function as the means for holding the metal strips of each bar 20 together.

It will be evident from the foregoing that when the nuts 22 are drawn up tightly they tend to pull the two bars 20 toward each other and thereby place the tie members 17 under tension. That tensile stress is transmitted to the outer door pan, making a structure that is extremely rigid in the plane of the door. Due to the peculiar construction of the equalizer, however, the stresses imposed upon the tie member 17 and the door pan 10 are equalized at the four corners of the door. Thus, there is no tendency for the door to be pulled out of its substantially rectangular shape when the nuts are drawn up on the bolts. The stiffening means only braces the door in the plane thereof so that when hung upon the refrigerator cabinet by the usual hinges at one side, the door will not tend to sag.

The stiffening means does not prevent the door from being warped to a limited extent in a direction perpendicular to the door. Not only that, but when the door is thus warped it will maintain its warped condition. Thus, even when the door does not touch the cabinet about its entire perimeter when first hung on the cabinet, the door can be warped sufficiently to make a tight contact throughout the perimeter of the door and it will maintain that shape unless distorted by some external force.

The door is completed by an inner door panel 25, preferably of sheet plastic or other similar heat insulating material. The inner door panel shown is provided with a convex rib 26 extending entirely around the door panel and spaced from the perimeter thereof. The rib 26 tends to ornament the inner door panel and at the same time permits slight expansion and contraction thereof without buckling.

The inner door panel 25 is supported on the door by two ornamental moldings 27 and 28. The molding 27 is formed to the cross section shown in Figures 5 and 6. It is U-shaped in elevation and extends about the top and two upright sides of the door. Preferably the molding is formed of relatively soft metal or other malleable material. It has an outer angular bead portion 29 adapted to engage a sealing gasket on the cabinet in the manner disclosed in my copending application Serial No. 518,051, filed January 13, 1944. Spaced from the bead 29 is a web 30 which forms, with the bead 29, an elongated channel shaped recess. The channel shaped recess is adapted to receive three sides of the perimeter of the inner door panel 25.

The free edge of the web 30 extends perpendicular to the latter to form a flange 31. This flange 31 is bent inwardly at spaced apart points and crimped over the upright leg of the reinforcement 18 to frictionally hold the molding upon the door. The entire flange 31 may be bent against the reinforcing member 18 if desired, but it is unnecessary to do that to hold the molding in place.

The bottom molding 28 is a straight one piece member formed to the cross-sectional configuration shown in Figure 7. It comprises a bead 32 similar to bead 29 and a web 33 spaced from and paralleling the bead 32. Together the bead 29 and web 33 form a channel to receive the bottom edge of the panel 25. The molding 28 is also provided with a flange 34 which extends beneath and parallels the bottom portion of the perimetrical side wall 12. The flange 34 is attached to

the side wall 12 and to the bottom part of the reinforcing member by screws 35.

After the molding 27 has been attached to the top and two upright sides of the door as described above, but before the molding 28 has been attached, the inner door panel 25 can be readily attached to the door by inserting the upper end of the panel into the lower ends of two sides of the molding and sliding it vertically in the recesses adapted to receive it. When the panel 25 is in position the lower molding 28 is slipped over the bottom edge of the door panel and is attached to the door by the aforesaid screws 35.

The door panel 25 is not crimped into the recesses within the various moldings, but is permitted a limited sliding movement therein. Thus, it will be seen that the door panel does not to any substantial extent reinforce the door nor interfere with the proper functioning of the stiffening means above described.

From the foregoing it will be seen that the present invention provides a novel means for stiffening a door in the plane thereof, yet permitting the door to be warped or flexed laterally so as to conform to the front of the cabinet when the door is closed and latched. The invention also provides a novel means for holding the inner door panel on the door without interfering with the proper operation of the stiffening means.

The scope of the invention is indicated in the appended claims.

I claim:

1. In combination, a door comprising a generally rectangular concavo-convex door pan composed of relatively flexible material and adapted to be supported from one lateral edge thereof, and means for stiffening said door pan in the plane thereof while permitting flexing in a direction normal to the plane thereof comprising a plurality of separate tie members connected at their ends remote from each other to said door pan at widely spaced points about the perimeter thereof, adjacent ends of said tie members being positioned adjacent the center of the door opening and spaced from each other, and adjustable equalizing means connected at spaced apart points to the adjacent ends of all of said tie members for placing the latter under stress and distributing said stress about the perimeter of the door pan.

2. A door as defined in claim 1 wherein said tie members are pivotally connected at their remote ends to said door and pivotally connected at their adjacent ends to said equalizing means.

3. A door as defined in claim 1 wherein there are four tie members arranged in pairs converging toward the center of the door, and said equalizing means comprising a pair of spaced apart substantially parallel bars, and means for drawing said parallel bars toward each other, each bar being connected adjacent its ends to adjacent ends of a pair of tie members.

4. In combination, a door comprising a generally concavo-convex door pan composed of relatively flexible material and adapted to be supported from one lateral edge thereof, reinforcing means for the perimeter of the door pan connected thereto, and means for stiffening said door in the plane thereof while permitting flexing in a direction normal to the plane thereof comprising a plurality of separate elongated tie members connected at their ends remote from each other to said reinforcing means at widely spaced points, adjacent ends of said tie members being positioned adjacent the center of said door and

spaced from each other, and adjustable equalizing means connected at spaced apart points to the adjacent ends of all of said tie members for placing the latter under stress and for distributing the stress about the perimeter of the door pan.

5. A door as defined in claim 4 wherein there are four tie members arranged in pairs converging toward the center of the door, and said equalizing means comprises a pair of spaced apart substantially parallel bars and means for drawing said parallel bars toward each other, each bar being connected adjacent its ends to adjacent ends of a pair of tie members.

6. In combination, a door comprising a generally rectangular concavo-convex door pan composed of relatively flexible material and adapted to be supported from one lateral edge thereof, and means for stiffening said door pan in the plane thereof while permitting flexing in a direction normal to the plane thereof comprising four tie members arranged in converging pairs, each pair of tie members being connected at their ends remote from each other to said door adjacent ad-

joining corners thereof and converging toward the center of the door, a bar pivotally connected at spaced apart points to the ends of one pair of tie members adjacent each other, a second bar pivotally connected at spaced apart points to the ends of the other pair of tie members adjacent each other, and spaced apart means connecting said bars together and for adjusting the distance between said bars.
